(57) **CLAIM**

The ornamental design for an audio and docking station for a handheld electronic device, as shown and described.

DESCRIPTION

FIG. 1 is a perspective view of an audio and docking station for a handheld electronic device showing my new design;

FIG. 2 is a front elevational view thereof;

FIG. 3 is a side elevational view of one side thereof;

FIG. 4 is an opposite side elevational view thereof;

FIG. 5 is a top plan view thereof;

FIG. 6 is a perspective view illustrating the positioning of a handheld electronic device docked thereon;

FIG. 7 is a front elevational view thereof;

FIG. 8 is a side elevational view thereof;

FIG. 9 is a top plan view thereof; and,

FIG. 10 is a partial, enlarged perspective view of the docking post.

The broken line showing of the docking post, button controls and handheld electronic device are included for the purpose of illustrating unclaimed portions of the article and environment of the article and forms no part of the claimed design.
